UNITED STATES PATENT OFFICE.

CHARLES F. PAIGE, OF OAKLAND, CALIFORNIA, ASSIGNOR OF ONE-THIRD TO ADOLPH W. JONES, OF OAKLAND, CALIFORNIA.

CONCENTRATOR.

1,140,764.

Specification of Letters Patent. Patented May 25, 1915.

Application filed May 5, 1914. Serial No. 836,444.

To all whom it may concern:

Be it known that I, CHARLES F. PAIGE, a citizen of the United States, residing at Oakland, in the county of Alameda and State 5 of California, have invented new and useful Improvements in Concentrators, of which the following is a specification.

This invention relates to concentrators and particularly to ore concentrators of the 10 type involving a shaking table, although it will be seen that the invention is applicable to stationary tables and sluices.

It is one of the objects of the present invention to provide a concentrating apparatus, whereby the pulp may be subjected to an action for stratifying the constituents of the pulp and for separating the concentrates from the gangue.

It is a particular object of the present invention to provide, in combination with a stratifying apparatus, means for facilitating the separation of slimes and gangue from the concentrates or valuable constituents of the pulp by the action of an aerated 25 current.

A further object is to provide, in a concentrating apparatus, a means providing a substantially closed chamber through which oppositely moving currents of liquid may be 30 maintained; one current moving with and carrying the concentrates, while an oppositely flowing current in the chamber effects a separation of the gangue and slimes from the chamber and removes them at the opposite 35 site end of the chamber from the discharge of the concentrates.

A further object is to provide a means providing a substantially closed chamber, in which are formed counter-currents of liquid, and to project into the chamber a jet 40 of liquid, under pressure, which causes the creation of the counter-current and also induces a flow of air, which operates, in conjunction with the counter-current, for the separation of the gangue from the pulp, and aids in the removal thereof and of flocculent material from the closed chamber.

The invention consists of the parts and the construction and combination of parts 50 as hereinafter more fully described and claimed, having reference to the accompanying drawings, in which—

Figure 1 is a plan view of the improved concentrating table. Fig. 2 is a side elevation thereof, showing the table operating

mechanism. Fig. 3 is a view of the table from the feed end. Fig. 4 is a plan view in detail of the counter-current and separating chamber. Fig. 5 is a central longitudinal section thereof. Fig. 6 is an end view of 60 Fig. 4.

2 is a concentrating table, or other suitable concentrating surface, inclined to a suitable degree, which may be of suitable proportions and construction and which 65 may or may not be given a shaking movement. If designed to shake or vibrate, appropriate mechanism is employed, indicated generally at 3; the table being mounted upon suitable supports 4. The upper surface of the table is shown as provided with a number of longitudinally spaced, shallow boxes or chambers, indicated generally at 5, which form the particular subject-matter of this invention; these boxes or chambers 70 forming traps or pockets for the segregation, classification and collection of values, as later described.

Referring to Figs. 4, 5 and 6, each of the boxes or chambers is shown as comprising a 80 bottom 6 and a top or cover 7, preferably of transparent material, the vertical walls 8 of the chamber being of such a height as to form a comparatively shallow structure and converge from the forward or feed end of 85 the table 2 rearwardly where they terminate in a discharge pocket. From the pocket end is extended a discharge tube 9, shown as vertically adjustable in a threaded bearing or flange 10 of the bottom of the chamber 5. 90 The function of the vertically adjustable tube 9 is to control the depth to which the stratification of concentrates may be maintained in the separating chamber 5.

Upon the forward end of the chamber 5 95 there is provided an adjustable cap or head-sheet 11 with slots 12 through which fastening screws 13 extend into the vertical walls 8. The rear edge of the head-plate 11 is movable toward and from the adjacent 100 transverse front edge of the transparent chamber cover 7, which is shown as upwardly beveled at 14. The space between the rear edge of the head-plate 11 and the head end of the top 7 forms a discharge 105 aperture from the chamber or box 5 for the liquid of the pulp which feeds into the chamber 5 in the direction of arrow *a*, Fig. 5.

For aiding the stratification of the mineral in the pulp, in conjunction with the 110

stratifying effect of the shaking table 2, a multiplicity of staggered vertical pins 15 are mounted in the bottom 6 of the chamber 5, the pins being of various diameters and various heights. The longer and largest pins are disposed at the feed end of the chamber and the remaining pins are of less height and diminish in size toward the discharge end.

10 Transversely mounted adjacent to the rear end of a concentrating chamber 5 is a tube or pipe 16, which is here shown as provided with a tangential and horizontally directed nozzle or spray mouth 17. Water under pressure is supplied through the transverse pipe 16 through a suitable supply pipe 18; one end of the nozzle pipe 16 being extended from the chamber 5 at one side and provided with an operating handle 19, whereby the pipe 16 may be turnably adjusted in its bearings to cause the nozzle 17 to discharge its jet at a suitable angle upstream in the chamber 5 as may be desired. The nozzle 17 will then discharge a jet of water under pressure from the pipe 16 into the chamber 5, below its transparent cover 7, the jet causing a counter-current moving in the direction of arrow b, Fig. 5, which aids in the separation of the slimes and gangue from the mineral concentrate which has been stratified upon the bottom 6 of a concentrating chamber resulting from the shaking movement of the table 2.

For further aiding the separation of the values from the valueless contents of the pulp I have provided means for the introduction of air at the discharge end of the concentrating box or chamber. This means comprises, in the present instance, air passageways 20, a suitable number of which may be provided at a desirable location and here shown as being in the upper end of the discharge pipe 9. Thus while the downwardly moving stream of concentrates on the bottom 6 of the concentrating chamber approaches the discharge end of the pocket the concentrates discharge through the tube 9. When a jet of water is being discharged from the nozzle 17 a suction effect is produced in the discharge spout 9, and while the heavy concentrates discharge therethrough an up stream of air will be induced through the air passageways 20. The air passes into the pocket 8 over the concentrates and moves toward the spray nozzle 17 where the incoming air is intimately mixed with the jet at the nozzle and the upper counter-current is charged with air bubbles which act to accelerate the upper counter-current, agitate the liquid and gangue in the chamber, and thus quicken the discharge of gangue through the discharge aperture at the head of the plate 11.

As many of the individual separating boxes 5 may be provided as is desired longi-

tudinally upon the table 2; the discharge stream from the pulp orifice of one box passing over the top thereof down the table 2 to the next box. By adjusting the head-plate 11 of each of the boxes the quantity of pulp treated in each box may be carefully determined and each box treat only a portion of the whole quantity of pulp fed to the table; some of the pulp passing into the first separating box and some passing over it down to the next box, and so on the full length of the table, until the pulp has been treated to a concentrating and separating action which its characteristics determine.

For the purpose of directing the heavy contents of the pulp quickly to the intake or feed end of the concentrating box 5, there may be provided, upon the table 2 and at opposite sides, suitable wave-forming deflectors, indicated at 21, the convergent and opposite edges of which are downwardly beveled, as at 22. These inclined walls react upon the pulp to form waves or ripples which cause the stratified portion of the pulp to drift toward the center of the table and down into the entrances of the separating boxes 5.

Having thus described my invention, what I claim and desire to secure by Letters Patent is—

1. In a concentrating apparatus, the combination with a suitable concentrating surface over which the material to be separated is adapted to flow, of means including an open-mouth pocket in the path of the materials passing over the concentrating surface having a cover, a discharge for the values collecting in the pocket, and means for creating a counter-current of air and water through the pocket in the direction of the mouth of the pocket to carry the flocculent material out of the pocket onto the concentrating surface again.

2. In a concentrating apparatus, the combination with a movable support, of a substantially closed chamber or box having an opening at one end for infeeding pulp and a discharge aperture for concentrates at the opposite end and an orifice at the top of the chamber for the discharge of that portion of the pulp from which the concentrates have been separated, and means for introducing a stream of water in and between the top and bottom of the box in counter-direction to the pulp, whereby the values are separated from the pulp and the gangue washed back through said orifice while the values move downward along the bottom of the box to said aperture.

3. In a concentrating apparatus, a shallow, slightly inclined, substantially closed chamber with a pulp inlet aperture, a discharge aperture for the concentrates at the bottom, a variable discharge orifice for the gangue at the top, and means for producing

counter-currents of air and water in the pulp in the chamber, including an angularly adjustable jet nozzle and an air inlet fitting.

4. In a concentrating apparatus, a substantially closed chamber with a pulp inlet aperture, a discharge aperture for the concentrates at the bottom, a discharge orifice for the gangue at the top, and means for producing counter-currents in the pulp in the chamber and for inducing air into the chamber and mixing it with the counter-currents.

5. In a concentrating apparatus, a substantially closed, shallow chamber having a feed inlet, a discharge outlet for concentrates at the opposite end of the chamber from the inlet, a discharge orifice at the top for the discharge of gangue, and means for producing an aerated counter-current in the chamber.

6. In a concentrating apparatus, a substantially closed, shallow chamber with baffle members projecting upwardly from its bottom and having a feed inlet, a discharge outlet for concentrates at the opposite end of the chamber from the inlet, a discharge orifice at the top for the discharge of gangue, and means for producing an aerated counter-current in the chamber.

7. In a concentrator and separator, a substantially closed, comparatively shallow chamber, with a top, having an inlet opening at one end and a discharge spout at the bottom and opposite end for concentrates and a variable discharge orifice in the top and adjacent to the inlet end for gangue, and means for producing a counter-current in the chamber moving in opposition to the direction of travel of the concentrates.

8. In a concentrator and separator, a substantially closed, comparatively shallow chamber, with a top, having an inlet opening at one end and a discharge spout at the bottom and opposite end for concentrates and a variable discharge orifice in the top and adjacent to the inlet end for gangue, and means for producing a counter-current in the chamber moving in opposition to the direction of travel of the concentrates, said discharge spout being adjustable in the bottom of the chamber.

9. In a concentrator and separator, a substantially closed, comparatively shallow chamber, having an inlet opening at one end and a discharge spout at the bottom and opposite end for concentrates and a discharge orifice in the top and adjacent to the inlet end for gangue, means for producing a counter-current in the chamber moving in

opposition to the direction of travel of the concentrates, said discharge spout being adjustable in the bottom of the chamber, and means for admitting air into the lower end of the chamber for mixture with the counter-moving current.

10. In a concentrating apparatus the combination of a concentrating surface over which the material to be separated is adapted to flow, and provided with a discharge for the collected solids, and air inlet means, a nozzle arranged close to but spaced from the concentrating surface and adapted to direct a current of water over and upon the surface of the flowing liquid, to create a flow of bubbles toward the feed end to carry the flocculent material away from said solids discharge.

11. In a concentrating apparatus the combination of a concentrating surface over which the material to be separated is adapted to flow, and provided with a discharge for the collected solids, and air inlet means, a nozzle arranged close to but spaced from the concentrating surface and adapted to direct a current of water over and upon the surface of the flowing liquid, to create a flow of bubbles toward the feed end to carry the flocculent material away from said solids discharge, a housing forming a pocket for the nozzle and said solids discharge and open toward the feed end of the apparatus, and a series of pins in the pocket and projecting upward from the concentrating surface.

12. In a concentrating apparatus, the combination of a horizontally disposed chamber having a flat bottom and slightly inclined from the feed end to the discharge end and through which liquid may flow, the chamber having flared sides wider at the feed end, a flat transparent cover for the chamber beneath which the flow takes place, and a nozzle beneath the cover and adjacent to the discharge end of the chamber for directing a counter surface current in the chamber in the direction of the feed end, and said cover having a transverse slot between said feed end and discharge and through which the said counter flow may discharge, substantially as described.

In testimony whereof I have hereunto set my hand in the presence of two subscribing witnesses.
